SCAFFOLD JACK

Reinhold A. Uecker, Ingar G. Rambo, and David E. Beatty, Wauwatosa, Wis.

Application September 19, 1938, Serial No. 230,649

3 Claims. (Cl. 304—37)

This invention relates to scaffold jacks and more particularly to a scaffold jack adapted to compensate for variations in elevation of a scaffold foundation.

5 One object of the present invention is to provide a jack to raise the bottom of a scaffold and hold the scaffold rigidly in position.

Another object is to provide a scaffold jack which may be readily applied to the scaffold.

10 A further object is to provide a scaffold jack in which the danger of disengagement from the scaffold will be minimized.

Another object is to provide a jack for a scaffold which is adapted to fit between a standard base plate and the end of the scaffold.

15 Other objects will be apparent from the following description.

According to this invention the jack is made with a sleeve fixed on the end of the screw engageable with the interior of a scaffold post, and a nut on the screw having a collar formed thereon fitting within the post, the collar and sleeve cooperating to space the screw threads from the interior of the scaffold post and prevent wobbling 20 of the scaffold on the jack.

In the drawing:

Fig. 1 shows parts of two scaffold end frames with the jacks in place thereon;

Fig. 2 is an enlarged cross-section through a 25 scaffold post showing the jack positioned between the end of the scaffold post and a base plate;

Fig. 3 is a cross-sectional view of the upper end of the jack shown in Fig. 2;

Fig. 4 is an elevational view taken at right angles to Fig. 3;

Fig. 5 is a cross-section on the line 5—5 of Fig. 2 looking in the direction of the arrows; and

Fig. 6 is an elevational view of a coupling pin.

Referring to the drawing, the scaffold shown 40 is of the sectional type in which a plurality of end frames 10 are superimposed upon each other to build a tower to any height. Such a scaffold is fully described in the U. S. patent to Reinhold A. Uecker, Serial No. 2,043,498, issued June 9, 1936.

45 As shown, each end frame comprises a pair of vertical posts 11—11, spaced apart and held in spaced parallel relationship by horizontal braces 12—12.

On uneven ground it is sometimes necessary to 50 jack up one or more posts of the scaffold so that the resulting tower will be truly vertical.

The jack which forms the subject matter of this invention comprises a screw 14, over the upper end of which is fixed a sleeve 15 having a 55 working fit within the post 11. On the lower end of the screw 14 is a nut 20.

of the screw is fixed a second sleeve 16 having substantially the same inside diameter as the post, and engageable over a standard base plate 18. A nut 20 fits on the screw 14 and adjusts the position of the bottom of the post 11 relative 5 to the base plate.

The screw 14 fits within the sleeve 15 and is fixed therein, preferably by welding. A spring retaining member 22 is positioned within the sleeve 15, and projects out through a slot 23 in the wall 10 of the sleeve to grip the interior of the post 11 and prevent accidental disengagement of the jack from the scaffold.

The sleeve 16 has an interior diameter preferably the same as the interior diameter of the 15 post 11 so that it can receive the standard base fitting 18 or a coupling pin 24 and be held in engagement therewith by a spring retaining member 25 formed in the upstanding pin 26 of the base plate 18.

20 The nut 20 is formed with an upstanding collar 27 on the upper end of the nut which terminates at its lower end in a shoulder 28. The collar 27 receives the interior of the post 11 while the shoulder 28 forms a base upon which the 25 post rests.

The collar 27 thus cooperates with the sleeve 15 to form a unitary rigid column, and prevents wobbling of the screw 14 within the post. The sleeve 15 and the collar 27 also serve to space 30 the screw from the interior of the post and so prevent damage to the threads.

The nut 20 may be provided with handles 30—30 to facilitate turning the nut and adjusting its position on the screw 14.

35 It is obvious that the jack may also be used to support a second end frame 10 by mounting the lower sleeve 16 of the jack over the coupling pin 24 (Fig. 1) in the top of one frame, and mounting a second frame over the sleeve 15 and onto 40 the shoulder 28.

Having thus described the invention it is hereby claimed as follows:

1. In a scaffold jack for use with a scaffold having a tubular post, a screw, a sleeve fixed on 45 one end of said screw and engageable with the interior of said post, a nut adjustable on said screw, a collar on said nut rotatably engageable with the interior of said post, and means to releasably retain the sleeve within the post. 50

2. A jack for use with a scaffold having a vertical post and a scaffold member having a tubular pin connected therewith, said jack comprising a screw, a first sleeve fixed on one end of said 55 screw and engageable with the interior of said

post, a second sleeve on the other end of said screw engageable over said pin, a nut adjustable on said screw, and a collar on said nut engageable within the post and co-operating with the first named sleeve to retain the screw in alignment with the post and to maintain the post and the scaffold member in spaced relationship.

3. In a scaffold jack for use with a scaffold having a tubular post, a screw projectable into said post, a sleeve fixed on said screw and engageable

with the interior of said tubular post, a nut adjustable on said screw, and a collar formed on said nut rotatably engageable with the interior of said post, said sleeve and said collar cooperating to maintain the threaded portion of said screw spaced from the interior of said post.

REINHOLD A. UECKER.
